US00D976256S

(12) **United States Design Patent** (10) Patent No.: **US D976,256 S**
Han (45) Date of Patent: ** Jan. 24, 2023

(54) **SMARTWATCH**

(71) Applicant: **Zhongtao Han**, Shenzhen (CN)

(72) Inventor: **Zhongtao Han**, Shenzhen (CN)

(**) Term: **15 Years**

(21) Appl. No.: **29/770,007**

(22) Filed: **Feb. 9, 2021**

(30) **Foreign Application Priority Data**

Jan. 25, 2021 (CN) 202130051275.9

(51) **LOC (14) Cl.** **14-02**

(57) **CLAIM**

The ornamental design for a smartwatch, as shown and described.

DESCRIPTION

FIG. 1 is a perspective view of a smartwatch showing my new design;

FIG. 2 is another perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right side elevational view thereof; and,

FIG. 8 is a left side elevational view thereof.

The broken lines in the drawings depict portions of the smartwatch that form no part of the claimed design.

1 Claim, 8 Drawing Sheets
